UNITED STATES PATENT OFFICE

2,387,847

SCORE INDICATOR

Harry E. Hoffman, Peoria, Ill.

Application February 28, 1944, Serial No. 524,255

1 Claim. (Cl. 235—122)

This device relates to a registering apparatus and particularly to a score indicator. Its principal object is to provide an accurate, simple and compact device, one comparatively cheap to manufacture and which may be very easily installed in the playroom or wherever desirable for its use.

Another object is to provide a score indicator which may be operated with a minimum of inconvenience to the contestants.

These and other objects will be made clear by a reading of the specification, taken in conjunction with the accompanying drawings, in which:

Figure 1 illustrates the position of the indicator with reference to the playing table.

Figure 2 is an end elevation of the device.

Figure 3 is a top plan view.

Figure 4 is a front elevation with the front cover plate removed, taken on the line 4—4 of Figure 2, and looking in the direction in which the arrows point, and

Figure 5 is a section taken on the line 5—5 of Figure 1 and looking in the direction in which the arrows point.

Referring to Figure 1, the numeral 1 indicates a play table, here illustrated as a table tennis or ping-pong table. The indicator may be used in connection with various types of games such as billiards, pool, etc. The indicator may be placed in any convenient location such as being fastened to a wall beside the table. As shown here, the indicator is fastened to the wall preferably near the ceiling so that it will not cause interference and may be easily viewed by the contestants. The score may be observed through the openings 3. Leading from the indicator are the cords 4 and 4a. Obviously, these cords may be extended to any desired point. The pulleys 5, 5a, 6 and 6a guide and permit of easy manipulation of the cords. The numerals 7 and 7a indicate handles for the cords 4 and 4a.

Referring to Figure 2 there is a back plate 11 and a front plate 12 which houses a toothed disk 13 at one side of the indicator and a similar toothed disk 14 at the opposite side thereof. Returning to Figure 2 there is a pawl element 15 in operative engagement with the disk. It might be stated, at this point, that in view of the fact both of the disk assemblies operates in an identical manner, only one assembly will be described. The only difference in the assemblies is that the disks will rotate in opposite directions. The pawl 15 is preferably made of flat metal, in order to snugly fit into the teeth 16, as clearly shown at 17, Figure 4, this snug fit being provided by the offset

portion 18. At the outer end of the offset is located a stop pin 19, which is held between the cover plates, this pin will stop the retractive movement of the pawl, which movement is provided by tension of the spring 20, the spring being connected to the lower end of the pawl, as indicated at 21. The lower end of the spring is securely fastened between the plates 11 and 12, in any convenient manner, as indicated by the numeral 22. Located near the upper end of the pawl, are two guide pins 23 and 24, arranged so that they will prevent undue strain on this portion of the pawl.

Cord 4 may be connected with the pawl in any conventional manner, such as with the S-hook 25.

Positioned between the two disks is the ratchet element 28, fixed by means of the supporting pin 29, which extends through an upward extension 30 of the ratchet 28, the extension 30 being integral with the ratchet. Ratchet 28 is preferably made of ordinary spring material and normally has its extremities 31 and 32 positioned in a tooth of each of the disks, as indicated by the numerals 33 and 34.

Figure 5 is an enlarged sectional view taken on the line 5—5 of Figure 1 and illustrates the means whereby but one numeral will be visible at a time, the dimension of the opening 35 being such that the visibility of the numerals will not overlap.

The operation of the device is, briefly, as follows. The position of the elements, shown in Figure 4, is when they are at rest and ready to be tripped. When a contestant pulls a handle 7 the pawl 15 will be raised, the offset 18 acting against a tooth 16 will rotate the disk 13 on its pivot 13a. The distance between the pins 19 and 24, the latter acting as a stop for the offset 18 in its upward movement, is such that the disk will be rotated the length of one tooth. During this movement the end 31 of the ratchet 28 will ratchet over the tooth 36 and will take a position on the following tooth, thereby preventing free movement of the disk, the resiliency of the ratchet 28 should be such that undue pressure will not be necessarily applied to the handle 7. Action of the spring 20 will return the pawl 15 to its original position on the following tooth.

It is believed to be evident that while the invention requires a minimum of parts its action is nevertheless very definite.

I claim:

In a device of the character described, a casing, a pair of rotatably mounted ratchet discs in said casing, said discs being toothed about their entire

periphery, a flat spring positioned between said discs, the ends of the springs engaging the teeth of opposite discs, a pawl positioned adjacent each of said discs, said pawls being on opposite sides of their respective discs, and each comprising an elongated member having two substantially right angled bends therein to form a shoulder, the inner side of said shoulder being adapted to engage the teeth of an associated ratchet disc, means secured to one extremity of each of said elongated members to move the same to cause said shoulder to rotate its associated ratchet disc, stop means limiting the forward movement of said

pawl to a distance slightly in excess of the length of a tooth, said means comprising a pair of spaced pins secured in said casing on opposite sides of each pawl, the spacing being less than in the extent of said shoulder, resilient means adapted to retract said pawl, and means limiting the distance to which said resilient means may retract said pawl, said last-mentioned means comprising a pin in said casing engageable by the 10 surface of said shoulder opposite the tooth engaging surface thereof.

HARRY E. HOFFMAN.
